UNITED STATES PATENT OFFICE.

ROBERT J. MARTIN, OF OSWEGO, NEW YORK.

GAME APPARATUS.

Application filed February 4, 1922. Serial No. 534,161.

To all whom it may concern:

Be it known that I, ROBERT J. MARTIN, a citizen of the United States, residing at Oswego, in the county of Oswego and State 5 of New York, have invented certain new and useful Improvements in Game Apparatus, of which the following is a specification.

This invention appertains to certain improvements in game apparatus generally, and more particularly to a type of the same requiring skill on the part of an operator to obtain a high or winning accumulative score in each cycle of operation thereof. 10
The principal object of the invention is to provide for an apparatus of the class mentioned, and one of an arrangement combining simplicity and efficiency in operation, and durability in construction, with 15
comparative low cost in manufacture and maintenance.

Another object of the invention is to provide for a game apparatus as characterized, and one involving a novel and efficient form 20
of coin control mechanism for effecting the release of the playing devices successively for each coin inserted into the control mechanism, and which automatically locks after each cycle of playing of the game 25
and in a manner to prevent any and all possible chance for the operation of the apparatus without the insertion of a coin 30
into the said control mechanism.

With the foregoing, and other objects in 35
view, the invention resides in the certain novel and useful construction and arrangement of parts as will be hereinafter more fully described, set forth in the appended claims, and illustrated in the accompanying 40
drawings, in which:

Figure 1 is a top plan view of a preferred embodiment of the game apparatus, and with portions of the casing and parts broken away to show the interior arrangement thereof, 45

Fig. 2 is a vertical longitudinal section taken on the line 2—2 of Fig. 1,

Fig. 3 is a similar section taken on the line 3—3 of Fig. 1,

Fig. 4 is a fragmentary vertical longitudinal section taken on the line 4—4 of Fig. 1, and showing the ball control slide in its initial or locked position of operation, whereby, to prevent the delivery of the 50
balls to the shooting mechanism,

Fig. 5 is a similar view, but shows the

ball control slide in its unlocked position, whereby, the balls are delivered to the shooting mechanism,

Fig. 6 is a fragmentary sectional detail 60 taken on the line 6—6 of Fig. 1, and showing the control device for effecting the delivery of the balls individually to the shooting mechanism, and after the same has been released for play by the actuation of 65 the coin control mechanism,

Fig. 7 is a plan view of the upper face of the ball control slide device,

Fig. 8 is a transverse section taken on the line 8—8 of Fig. 7, 70

Fig. 9 is a fragmentary longitudinal section taken on the line 2—2 of Fig. 1, and showing the coin controlled device or mechanism in its normal position of operation.

Fig. 10 is a similar view, but showing 75
the operation of the locking device to prevent the manipulation of the coin slide for the actuation of the ball control slide and consequently the putting into play of the apparatus, and,

Fig. 11 is another similar view, showing the operation of the coin slide, after the coin has been properly positioned thereon, and the manner in which the coin effects 85
the release of the locking device, for the subsequent actuation of the ball control slide.

Referring to the drawings, wherein similar characters of reference designate corresponding parts throughout the several 90
views thereof, the preferred embodiment of the invention as shown comprises a casing or cabinet formed to provide a main compartment 15, for housing the game or main portion of the apparatus, and an auxiliary 95
compartment or coin chamber 16, for the reception of the coin control mechanism and for receiving the coins from the latter, during the successive manipulations thereof.

This casing or cabinet comprises an outer 100
side wall 17, and an intermediate side wall 18, of the same size and configuration of the wall 17, and between which, is formed a main compartment 15, as aforesaid. A second outer side wall 19, is provided, and the same is spaced from the intermediate wall 16 to form between the same, the auxiliary 105
compartment or coin chamber 16. The rear vertical edges of the outer side wall 17, and the intermediate side wall 18, are connected 110
by a back wall 20, while a rear vertical edge of the outer side wall 19, which is of a less

length than the walls 17 and 18, is connected to the intermediate wall 18, by means of a back wall 21. The top edges of the side wall 17 and the intermediate wall 18, are formed to provide horizontally disposed portions, extending inwardly from the rear vertical edges thereof, and has secured thereon, a top closure in the form of a frame 22, the latter having a glass insert 23, closing the opening thereof substantially as shown. The forward top edge portions of the walls 17 and 18, are forwardly and downwardly declined from the forward ends of the horizontal rear portions of the same, and the opposed faces of these walls 17 and 18, are provided with grooves 24 for the seating therein of a closure seat or plate of glass 25, whereby the game mechanism within the compartment 15 is entirely exposed to view.

20 The front vertical edges of the walls 17, 18 and 19, all terminate in the same plane, and are connected by a front wall 26, and all of the several walls forming both compartments 15 and 16 are mounted on a common bottom wall 27. The rear end portion of the outer side wall 19 of the compartment 16, is of a greater height than the forward portion thereof, and secured on the upper edges of the rear portion of the wall 19 and the rear wall 21, is a closure wall 28, which is supported at its forward edge on a strip 29, forming the front wall of the raised portion of the compartment 16. The forward upper open side of the compartment 16 is closed by means of a wall 30 secured on the upper edges of the front wall 26, and the forward upper edge portion of the outer side wall 19. The lower ends of the forwardly declined top edges of the outer side wall 17 and the intermediate wall 18, terminate in a common plane inwardly of the front vertical edges thereof, and the forward portions of these top edges are extended in the horizontal plane of the top edge of the front wall 26, whereby to have secured thereon an extended portion 31 of the closure wall 30, which consequently extends the full width of the casing or cabinet. The closure wall 30 is cut away at its inner side, and to cover the opening formed by the removal of the portion so cut away, a closure wall 32 is superposed on the upper side of the wall 30, and the forward edge of the same is extended to a point inwardly from the front edge of the wall 30, substantially as shown.

60 Mounted within the main compartment 15 is a runway formed of a length of sheet metal 33, which is secured at its front edge to the inner side of the front wall 26, and curves rearwardly and upwardly, so as to have its major length extending on the same general inclination as that of the glass closure plate 25, with its upper and rear end portion 34 curving slightly downward and into a bead-

ed edge 35, formed by the bending of the free edge of the metal in the downward and forward directions. This runway 33, extends the full width of the main compartment 15, and has its opposite side edges 70 formed to provide depending ears or tongue portions 36 by means of which it is supported throughout its full extent from the opposed faces of the walls 17 and 18, of the casing or cabinet, and the upper surface of 75 the runway 33, is preferably covered with a sheet of fabric 37, such as felt, billiard cloth, or the like.

The rear edge of the runway 33 is spaced above and overhangs the forward end of a rearwardly inclined plate 38, which has its opposite side edges formed to provide depending ears or tongues 39, by means of which the same is secured in position between the walls 17 and 18, of the main compartment 15, while its forward end edge is formed to provide an up bent angular flange 40, and its rear end edge is bent downwardly and forwardly to provide a bead-like finish thereto. Mounted on the transverse center of this plate 38 is a block of wood or the like 41, upon which is positioned an open frame or score box of the same configuration and of a size to have its opposite side and end walls firmly resting on the side and end edges of the upper face thereof. The block 41 is of a length equal to the width of the plate 38, and has its forward and rear side edges spaced at approximately equal distances from the corresponding edges thereof, and, as shown, the upper face of the plate is covered with a sheet of fabric 42 of billiard cloth, felt or the like. The open frame or score box has its rear side wall 43 hinged as at 44 to the rear side edge of the block 41, and this wall 43 is of a greater height than the front side wall 45, while the end walls 46, 46', have their upper edges inclined upwardly from the plane of the top edge of the front wall 45 and terminates in the plane of the top edge of the rear wall 43. The frame thus constructed and mounted is divided into a series of compartments by means of partition walls 47, each having the same configuration as that of the end walls 46, 46', and the inclination of the frame is such that the lower end portions of the compartments therein are disposed directly in line with the upper surface of the portion 34 of the runway 33. 120

The lower or forward end edge of the runway 33 is supported on a bar or strip 48 secured horizontally of the inner face of the front wall 26, of the casing or cabinet, and, in turn, supports thereon a member 49, preferably in the form of a block of wood, which has its inner edge cut on oppositely disposed diagonally extending lines and in a rearward direction from a centrally disposed recess 50, which is arranged in the 130

plane of the longitudinal center of the runway 33. Passed inwardly of the front wall 26, and through the member 49 in a manner to have its inner end project outwardly and centrally of the recess 50, is a firing plunger 51 having a hand grip 52 on its end projecting outwardly of the front wall 26, and surrounding the plunger 51 is a coil spring 53 normally tensioning the same to its innermost position, which is limited by the hand grip 52 abutting the outer face of the front wall 26. The opening in the front wall 26, and the passageway 54 through the member 49, is of a construction and arrangement, whereby to admit of a limited amount of lateral play to the firing plunger 51, upon the manipulation of the hand grip 52 for the purpose of aiming the plunger 51 for the shooting of balls *a* positioned singly in front of the recess 50, of the member 49, upwardly of the runway 33 and into any one or more of the several scoring compartments of the frame hinged to the block 41.

The balls *a*, when shot into the several scoring compartments of the hinged frame, are allowed to fall into the trough formed by the flange 40 at the forward edge of the inclined plate 38, by the upward swinging movement of the frame on its hinges 44, which admits of the balls *a* passing under the raised forward wall 45 and rolling over the edge of the block 41 for the purpose, and, by reason of the plate 38 declining slightly in the direction of the intermediate wall 18, of the cabinet, the balls *a* pass from the trough and through an exit opening 55 formed in the latter, and from thence take position one in rear of the other on a metal guideway 56 secured in position on the opposite side of the wall 18 and within the auxiliary compartment or coin chamber 16. This guideway 56 has a bottom wall declining slightly in the forward direction and has its inner edge formed to provide a depending flange 57, by means of which it is fastened in position, with its outer side and rear end edges upturned to provide a flanged wall 58 for directing the movement of the balls *a* from the guideway 56 when desired. Spaced beyond the forward open or discharge end of the guideway 56 is an abutment or stop bracket 59 which acts to retain the balls *a* in position on the guideway 56, until the same are put into play as will be hereinafter more readily apparent.

Secured horizontally along the wall 18, within the auxiliary compartment or coin chamber 16, is a trackway 60 in which is slidably mounted a ball control slot or member 61, which is normally disposed in its extreme forward position so that its rear end is positioned immediately below the space provided between the front end of the guideways 56 and the abutment 59, whereby, when the balls *a* are confined within and between

the latter, the first of the balls contacts the abutment 59 and rests on the upper portion of the upper of a pair of stepped and forward declining surfaces 62 and 63 formed in the top edge of the control block or member 61. These declined surfaces 62 and 63 are formed at the inner side of the block or member 61 in a manner to provide an outer wall 64 which acts to guide the balls *a* in their rolling movements to positions one in rear of the other thereon, when the block or member is moved rearwardly to bring the upper end of the lower declined surface 63 under the space between the front end of the guideway 56 and the abutment 59, in which position, the balls *a* are free to pass under the latter for the purpose. The lower end of the lower of the declined surfaces 63 terminates in a laterally and inwardly declined portion 65, while the vertical wall of the forward portion of the block or member 61 is cut on a diagonal line, as at 66, whereby the balls *a* are deflected, and pass singly from the block or member 61 through an exit opening 67 formed in the intermediate wall 18, when the latter is moved or slid to its forward position.

In the feeding of the balls *a* singly from the opening 67 and the slide block or member 61, a plunger 68 is passed inwardly of the front wall 26, of the cabinet, within the main compartment thereon, and in close parallel relation to the intermediate wall 18. The inner end portion of the plunger 68 projects inwardly and centrally of a squared opening 69, formed in a transversely disposed bar or strip 70, which is spaced inwardly from the front wall 26 and is secured in position between the closure portion 31 and the member 49, and through this opening into a housing 71 arranged in front of the opening 67, the inner side of the housing 71 being opened, and the interior thereof being square and of the same transverse area as that of the square opening 69 in the bar or strip 70. Mounted on the inner end of the plunger 68 is a block 72 of a size to be freely slidable in the square interior of the housing 71 and the opening 69, and this block 72 is normally disposed in a manner to close the exit opening 67 to prevent the balls *a* from entering the main compartment until desired or needed. Positioned on the plunger 68 and interposed between the block 72 and the inner face of the front wall 26, is a coil spring 73, which acts to normally tension the block 72 and the plunger 68 in their innermost positions. The outer end of the plunger 68 is projected through the front wall 26 and is provided thereon with a hand grip 74, which has its inner end normally abutting the outer face of the front wall 26 to limit the inward movement of the plunger 68, and by means of which the same is

manipulated. By grasping the hand grip 74, the plunger 68 may be drawn outward against the tension of the spring 73, and the block 72 moved to uncover the exit opening 67, when the first of the balls *a* will enter the housing 71 in the path of the plunger, and when the hand grip 74 of the latter is released, the spring 73 will expand and cause the block 72 to move or push the ball 10 out of the housing 71, and for a slight distance up the runway 33, when it will roll back down the latter and take position at the recess 50 in front of the inner end of the firing plunger 51. It is to be here 15 noted, that the coil spring 73 is of a less strength than the coil spring 53, cooperative with the firing plunger 51, so that, upon the manipulation of the ball feed plunger 68, a ball will be discharged upwardly of the runway 33 only for a short 20 distance, while upon the manipulation of the firing plunger 51, the force of its spring will propel the balls *a* fed thereto the entire length of the runway, and with sufficient 25 force to discharge the same into the scoring pockets in rear thereof.

The releasing of the balls *a* from the guideway 56 for delivery to the firing plunger 51 for play, is effected by a coin control mechanism which comprises a metal base plate 75, secured on the closure 30 adjacent the front edge thereof, and having a pair of oppositely disposed members or plates 76 extending inwardly at the opposite sides of the forward end of the same in spaced parallel relation, and formed at their inner opposed edges to provide raised flange portions 77 under which are slidably engaged the opposite side edges of a coin slide plate 78. The base plate 75 is elongated in a rearward direction and has its rear end angularly bent downwardly to provide a flange 79 engaged over the rear edge of the closure portion 30 and secured thereto by means of screws 80. The base plate 75 is also formed to provide a coin discharge opening 81 at a point medially of its ends and this opening is registered with an opening or recess 82 formed by a cutaway portion of the closure portion 30, and also with an elongated slotway 83 extending rearwardly from a point adjacent the coin opening 81 on its longitudinal center to a point spaced slightly inward of the flange portion 79 at the extreme rear end thereof. The coin plate 78 is slidable on the base plate 75, between the raised flange portions or trackways 77 formed by the members or plate 76 at the forward end thereof, and is guided in its sliding movements by means of a screw 84 secured in the under face of its rear edge and engaged in the longitudinal slotway 83 of the base plate. To admit of the sliding movement 60 of the head of the screw 84 along the under

side of the rear end portion of the base plate 75, a groove or channel 85 is cut in the upper face of the closure portion 30 rearwardly from the coin opening 82 communicating the interior of the auxiliary compartment 70 or coin chamber 16 of the cabinet. The coin slide member or plate 78 is formed at its forward end with an angularly upturned portion 86 to provide a finger grip for its manipulation, and at a point inwardly from 75 the portion or finger grip 86 with the coin receiving opening 87, which is adapted to register with the coin discharge openings 81 and 82, of the base plate 75, and the closure portion 30, when the coin plate 78 is moved 80 to its innermost position. Extending on the longitudinal center of the coin slide plate 78 and between the guide screw 84 and the coin opening 87 are a set of aligned slotted openings 88, 89 and 90, the openings 85 88 and 89 being separated one from the other by means of a connected portion 91, and the openings 89 and 90 by means of a connected portion 92, the forward edges 90 of these connected portions 91 and 92 being upwardly and rearwardly bevelled, and the rear edges thereof downwardly and forwardly bevelled substantially as is shown in Figs. 9 to 11, inclusive. Extending laterally from one side of the rear end portion of the coin slide plate 78, is an angularly bent arm 93, which has its free end portion secured, by means of a screw 94, to the upper edge of the side wall 64 of the ball control slide 61, substantially as is 100 shown in Figs. 1, 7 and 8. The opposite sides of the base plate 75 are formed to provide aligned laterally offset portions 95 at a point slightly forward of the transverse center thereof, and secured 105 in these portions 95 are depending portions formed at the opposite sides of a carrier plate 96, on which is mounted a locking mechanism for preventing the actuation of the coin slide plate 78 to full operative position until a coin *b* has been inserted into position within the coin opening 87. This carrier plate 96 is positioned to overlie an intermediate portion of the coin slide plate 78, and has formed on its longitudinal center, inwardly from the rear end thereof, an elongated slotted opening 97, in which is operable the rear free end portion 98 of a locking lever 99 having its forward end loosely secured under the head of a screw or stud 100 carried by the plate 96. The locking lever 99 is formed to provide a downwardly depressed portion 101 at a point intermediate its ends, and the free end of its rear portion 98, to provide a depending hook portion 102, which is undercut to provide a bevelled inner face corresponding to the rear bevelled edges of the connected portions 91 and 92 of the coin slide plate 78. The rear end portion 98 of the locking lever 99 is normally 110 115 120 125 130

depressed of the slotway 97, by the action of a spring finger 103 bearing on the lever 99 at a point slightly forward of the depressed portion 101, and which is secured in proper 5 position for the purpose at one side of the carrier plate by means of a stud or screw 104.

In the operation of the coin control mechanism, with the parts thereof as shown in Fig. 9, the pushing inward of the coin slide 10 plate 78 will result in the hook end 102 of the locking lever 99 engaging over the connected portion 92 substantially as is shown in Fig. 10, when the coin slide will be prevented from further inward movement, and 15 the movement of the same, while affecting a corresponding limited movement to the ball control slide 61; through the medium of the arm connection 93, is not sufficient to admit of the release of the balls *a* from the guideway 56 and the putting of the same into play. Now, in the event of the placing of a coin *b* of the proper size or value in the coin opening 87 of the coin slide plate 78, with the latter in the position as shown in Fig. 9, 20 by pushing in on the plate 78, the coin *b* will be carried along with the same, and will ride under the depressed portion 101 of the locking lever 99, raising the latter so that the hook end 102 is clear of the connected 25 portions 91 and 92, of the coin slide plate 99. Further inward movement of the coin slide 78 is now permitted to the full extent thereof, as shown in Fig. 11, and in final inward position, the coin opening 87 will register 30 with the coin opening 81, of the base plate 75, and the opening 82 of the closure portion 70, when the end portion 98 of the locking lever 99 will be free to be depressed under the tension of the spring finger 103, and will 35 snap downward into the opening 87, in the coin slide plate 79, and discharge the coin *b* into the auxiliary compartment or coin chamber 16 of the cabinet.

With the coin slide 78 positioned as in 40 Figs. 9 and 10, the ball control slide 61 is disposed in an intermediate position, or in its full forward position, whereby the balls *a* will be retained at the upper rear part of the same and on the guideway 56, and will remain so, regardless of the limited play of the coin slide plate 78, when no coin *b* has been positioned in the opening 87. However, upon the full rearward movement of the coin slide plate 78, as when a coin *b* has been placed in the coin opening 87 thereof, the ball control slide 61 will be moved rearwardly to a position whereby the balls *a* will roll from the guideway 56 and drop therefrom in rear of the abutment 59 onto the upper portion 45 of the lower incline surface 63 of the slide 61, upon which surface 63, the balls *a* (preferably six in number being provided for each cycle of play of the apparatus) will take position thereon. By now pulling outward on the coin slide plate 78, the ball slide 50 55 60 65 70 75 80 85 90 95 100 105 110 115 120 125 130

61 is drawn to its foremost position, when the lower end of the inclined surface 63 of the latter will register with the exit opening 67, and the first of the balls *a* will be deflected from the control slide and into the 70 opening 67 and in the position of the parts, the play of the apparatus can be accomplished.

To now play the game, after the operation of the coin control apparatus for the release 75 of the balls *a* as explained, the player will grasp the hand grip 74, pull out on the plunger 68, placing the spring 73 under compression, and moving the block 72 forwardly to uncover the exit opening 67 when the first of the balls *a* will roll through the opening 67 and take position within the housing 71, and in front of the plunger block 72, so that by releasing the hand grip 74, the spring 73 will expand and cause the 80 plunger to discharge the ball out of the housing 71 and onto the runway 33. The ball will now roll back down the runway 33, and take position in the recess 50 in front of the inner end of the firing plunger 51. The player will now manipulate the plunger 51 to discharge the ball up the runway 33 and into any one of the scoring compartments in the frame or score box disposed in rear of the upper end thereof. This operation 85 will be repeated until all six of the balls *a* have been fired, and the final score made, will be counted by the number of the compartments into which each ball has been lodged. As has been hereinbefore 90 explained, the firing plunger 51 may be swung sufficiently within its mounting to admit of the aiming of the same to discharge the balls *a* into any one of the several scoring 95 compartments. As shown, six of these compartments are provided, and if each are given the value of ten, then the total high score of the apparatus will be sixty, and this is to be so counted, when a ball has been lodged in each one of the several compartments. 100

For releasing the balls *a* from the scoring compartments, as by tilting the scoring frame or box on its hinges 44 as hereinbefore described, a cord or the like 104 is secured in an eye 105 carried at the center of the rear wall 43 of the scoring box or frame, and is trained therefrom rearwardly and downwardly over the beaded edge of the inclined plate 38 to an eye 106 secured in the upper surface of the bottom wall 27, and from thence is led forwardly of the main compartment 15 to an eye 107, also secured in the upper face of the bottom wall 27 at a point in line with the eye 106 and on the longitudinal center of the main compartment 16, where it is trained in a backward direction and diagonally of the compartment to an eye 108 projecting through a horizontally disposed slotway 109 formed 110 115 120 125 130

in the intermediate wall 18, and which eye 108 is carried by the ball control slide 61. As shown in Figs. 1 and 6, the cord 104 is provided with a certain amount of slack, which is taken up in that movement of the coin slide plate 78, when the same is illegally manipulated, as by the absence of a coin *b* from the coin slot or opening 87, so that the free movement of the coin slide 78 and the ball control slide 61 is permitted without in any way affecting the apparatus as a whole. When the coin slide 78 is manipulated with a coin *b* in position in the coin opening 87 thereof, the rearward movement of the ball control slide 61 therewith pulls on the cord 104, and raises the scoring box or frame to free the balls *a* from the scoring compartments thereof, and the balls will then drop from the block 41 and roll 20 along the flange 40, of the incline plate 38 to the exit opening 55 and through the same to positions in the guideway 56. The apparatus is now ready for the next cycle of play, which is to be accomplished by the 25 placing of a coin *b* in the opening 87 of the coin slide plate 78, and the proper manipulation of the latter as hereinbefore explained.

As shown in Figs. 2 and 3, to prevent the 30 balls *a* from being discharged over and in rear of the score box or frame from the upper end of the runway 33, a guard of wire mesh or the like 110 is positioned in vertical alinement with the top edge of the 35 rear wall 43 of the score box or frame, and this guard 110 connects at its upper end to a second guard of wire mesh 111, which is secured in position to protect the glass insert 23 extending forwardly of the guard 40 110, whereby all possible chance for the breakage of the glass by being struck by the balls *a* is eliminated.

From the foregoing, it will be readily apparent that, while a preferred embodiment 45 of the game apparatus has been described and illustrated herein in specific terms of construction, arrangement and operation, various changes in and modifications of the same may be resorted to without departing 50 from the spirit of the invention, or the scope of the claims appended hereto.

Having thus described the invention, what is claimed, is:—

1. In a game apparatus, a cabinet formed 55 with a main and an auxiliary compartment, means to provide an outlet leading from the main to the auxiliary compartment, means to provide an inlet leading to the main from the auxiliary compartment, playing devices 60 within said cabinet and delivered to and from the main from and to the auxiliary compartment, a slidable element for directing and releasing said devices for passage thereof through said inlet, means for delivering 65 said devices successively to said

main compartment when released by said element, means for projecting said devices when delivered to said main compartment, a coin controlled mechanism for effecting the operation of said element, and means 70 operated from said mechanism to effect the discharge of said devices from said main to said auxiliary compartment.

2. In a game apparatus, a cabinet formed 75 with a main and an auxiliary compartment, means to provide an outlet leading from the main to the auxiliary compartment, means to provide an inlet leading to the main from the auxiliary compartment, playing devices within said cabinet and delivered to and from the main from and to the auxiliary compartment, means within said auxiliary compartment to provide a guideway leading from said outlet to said inlet, a stepped slidable element for directing and releasing said devices for passage through said inlet, means for delivering said devices successively to said main compartment when released and directed by said element, means 80 for projecting said devices when delivered to said main compartment, a coin controlled mechanism for effecting the operation of said element, and means operated from said mechanism to effect the discharge of said projected devices from said main to said auxiliary compartment. 85

3. In a game apparatus, a cabinet formed 90 with a main and an auxiliary compartment, means to provide an outlet leading from the main to the auxiliary compartment, means to provide an inlet leading to the main from the auxiliary compartment, playing devices within said cabinet and delivered to and from the main from and to the auxiliary compartment, means within said auxiliary compartment to provide a guideway leading from said outlet to said inlet, a stepped 95 slidable element for directing and releasing said devices for passage through said inlet, means for delivering said devices successively to said main compartment when released and directed by said element, means for projecting said devices when delivered to said main compartment, a coin controlled mechanism for effecting the operation of said element, and means operated from said mechanism to effect the discharge of said projected devices from said main to said auxiliary compartment. 100

4. In a game apparatus, a cabinet formed 105 with a main and an auxiliary compartment, means to provide an outlet leading from the main to the auxiliary compartment, means to provide an inlet leading to the main from the auxiliary, playing devices within said cabinet and delivered to and from the main from and to the auxiliary compartment, a stepped slidable element for 110 directing and releasing said devices for de- 115

- livery through said inlet, mean for delivering said devices successively through said main compartment when released by said element, a hinged score box within said 5 main compartment, means for projecting said devices when directed to said compartment into said score box, a coin controlled mechanism for effecting the operation of said element to release said devices for delivery to said main compartment, and means for shifting said score box to effect the discharge of said devices therefrom for delivery thereof from said main to said auxiliary compartment through said outlet.
- 15 5. In a game apparatus, a cabinet formed with a main and an auxiliary compartment, means to provide an outlet leading from the main to the auxiliary compartment, means to provide an inlet leading to the main from 20 the auxiliary, playing devices within said cabinet and delivered to and from the main from and to the auxiliary compartment, a stepped slidable element for directing and releasing said devices for delivery through 25 said inlet, means for delivering said devices successively through said main compartment when released by said element, a hinged score box within said main compartment, means for projecting said devices 30 when directed to said compartment into said score box, a coin controlled mechanism for effecting the operation of said element to release said devices for delivery to said main compartment, means for shifting said score 35 box to effect the discharge of said devices therefrom for delivery thereof from said main to said auxiliary compartment through said outlet, and means within said auxiliary compartment to provide a guideway leading 40 from said outlet to said inlet.
6. In a game apparatus, a cabinet formed with a main and an auxiliary compartment, means to provide an outlet leading from the main to the auxiliary compartment, 45 means to provide an inlet leading to the main from the auxiliary, playing devices within said cabinet and delivered to and from the main from and to the auxiliary compartment, a stepped slidable element for 50 directing and releasing said devices for delivery through said inlet, means for delivering said devices successively through said main compartment when released by said element, a hinged score box within said 55 main compartment, means for projecting said devices when directed to said compartment into said score box, a coin controlled mechanism for effecting the operation of said element to release said devices for delivery to said main compartment, means for shifting said score box to effect the discharge of said devices therefrom for delivery thereof from said main to said auxiliary compartment through said outlet, and means within said auxiliary compartment to pro- 60 vide a guideway leading from said outlet to said inlet.
7. In a game apparatus, a cabinet formed with a main and an auxiliary compartment, means to provide an outlet leading to the main from the auxiliary, means to provide an inlet leading from the main to the auxiliary compartment, playing devices within said cabinet and delivered to and from the main from and to the auxiliary compartment, 65 a slidable element for directing and releasing said devices for passage through said inlet, a spring controlled member arranged at one side of said main compartment for delivering said devices successively when released by said element to said main compartment, a shiftable score box arranged within the main compartment, a spring controlled member disposed centrally at one end of the said main compartment for projecting said devices when delivered to said main compartment into said score box, a coin controlled mechanism for effecting the operation of the said element, and means operated from said mechanism for shifting 75 said score box to effect the discharge of said devices therefrom for delivery thereof through said outlet into said auxiliary compartment.
8. In a game apparatus, a cabinet formed with a main and an auxiliary compartment, means to provide an outlet leading to the main from the auxiliary, means to provide an inlet leading from the main to the auxiliary compartment, playing devices within said cabinet and delivered to and from the main from and to the auxiliary compartment, a slid- 80 able element for directing and releasing said devices for passage through said inlet, a spring controlled member arranged at one side of said main compartment for delivering said devices successively when released by said element to said main compartment into said score box, a coin controlled mechanism for effecting the operation of the said element, and means operated from said mechanism for shifting 85 said score box to effect the discharge of said devices therefrom for delivery thereof through said outlet into said auxiliary compartment.
9. In a game apparatus, a cabinet formed with a main and an auxiliary compartment, means to provide an outlet leading to the main from the auxiliary, means to provide an inlet leading from the main to the auxiliary compartment, playing devices within 90

said cabinet and delivered to and from the main from and to the auxiliary compartment, a slidable element for directing and releasing said devices for passage through said inlet, 5 a spring controlled member arranged at one side of said main compartment for delivering said devices successively when released by said element to said main compartment, a shiftable score box arranged within the 10 main compartment, a spring controlled member disposed centrally at one end of the said main compartment for projecting said devices when delivered to said main compartment into said score box, a coin controlled mechanism for effecting the operation of the said element, means operated from said mechanism for shifting said score box to effect the discharge of said devices therefrom for delivery thereof through said outlet 15 into said auxiliary compartment, an inclined support within said main compartment for said score box, an inclined runway leading from said members and extended over said support, and means within said auxiliary compartment to provide a guide way leading from said outlet to said inlet. 20 10. In a game apparatus, a cabinet formed with a main and an auxiliary compartment, means to provide an outlet leading to the main from the auxiliary, means to provide an inlet leading from the main to the auxiliary compartment, playing devices 25 within said cabinet and delivered to and from the main from and to the auxiliary compartment, a slidable element for directing and releasing said devices for passage through said inlet, a spring controlled member arranged at one side of said main compartment for delivering said devices successively when released by said element to said main compartment, a shiftable score box arranged within the main compartment, a spring controlled member disposed centrally at one end of the said main compartment for projecting said devices when delivered to said main compartment into said score box, a coin controlled mechanism for effecting the operation of the said element, means operated from said mechanism for shifting said score box to effect the discharge of said devices therefrom for delivery thereof through said outlet into said auxiliary compartment, an inclined support within said main compartment for said score box, an inclined runway leading from said members and extended over said support, means within said auxiliary compartment to provide a guideway leading from said outlet to said inlet, and a stop extended into said guideway. 30 11. In a game apparatus, a cabinet formed with a main and an auxiliary compartment, means to provide an outlet leading to the main from the auxiliary, means to provide an inlet leading from the main to the auxiliary compartment, playing devices 35 within said cabinet and delivered to and from the main from and to the auxiliary compartment, a slidable element for directing and releasing said devices for passage through said inlet, a spring controlled member arranged at one side of said main compartment for delivering said devices successively when released by said element to said main compartment, a shiftable score box arranged within the main compartment, a spring controlled member disposed centrally at one end of the said main compartment for projecting said devices when delivered to said main compartment into said score box, a coin controlled mechanism for effecting the operation of the said element, means operated from said mechanism for shifting said score box to effect the discharge of said devices therefrom for delivery thereof through said outlet into said auxiliary compartment, an inclined support within said main compartment for said score box, an inclined runway leading from said members and extended over said support, means within said auxiliary compartment to provide a guideway leading from said outlet to said inlet, and a stop extended into said guideway. 40 12. In a game apparatus, a cabinet formed with a main and an auxiliary compartment, means to provide an outlet leading to the main from the auxiliary, means to provide an inlet leading from the main to the auxiliary compartment, playing devices 45 within said cabinet and delivered to and from the main from and to the auxiliary compartment, a slidable element for directing and releasing said devices for passage through said inlet, a spring controlled member arranged at one side of said main compartment for delivering said devices successively when released by said element to said main compartment, a shiftable score box arranged within the main compartment, a spring controlled member disposed centrally at one end of the said main compartment for projecting said devices when delivered to said main compartment into said score box, a coin controlled mechanism for effecting the operation of the said element, means operated from said mechanism for shifting said score box to effect the discharge of said devices therefrom for delivery thereof through said outlet into said auxiliary compartment, an inclined support within said main compartment for said score box, an inclined runway leading from said members and extended over said support, means within said auxiliary compartment to provide a guideway leading from said outlet to said inlet, and a stop extended into said guideway. 50 13. In a game apparatus, a cabinet formed with a main and an auxiliary compartment, means to provide an outlet leading to the main from the auxiliary, means to provide an inlet leading from the main to the auxiliary compartment, playing devices 55 within said cabinet and delivered to and from the main from and to the auxiliary compartment, a slidable element for directing and releasing said devices for passage through said inlet, a spring controlled member arranged at one side of said main compartment for delivering said devices successively when released by said element to said main compartment, a shiftable score box arranged within the main compartment, a spring controlled member disposed centrally at one end of the said main compartment for projecting said devices when delivered to said main compartment into said score box, a coin controlled mechanism for effecting the operation of the said element, means operated from said mechanism for shifting said score box to effect the discharge of said devices therefrom for delivery thereof through said outlet into said auxiliary compartment, an inclined support within said main compartment for said score box, an inclined runway leading from said members and extended over said support, means within said auxiliary compartment to provide a guideway leading from said outlet to said inlet, and a stop extended into said guideway. 60

In testimony whereof, I affix my signature hereto.

ROBERT J. MARTIN.
